UNITED STATES PATENT OFFICE

MARJORIE TONES KNIGHT, OF DES MOINES, IOWA

DESIGN FOR A LAMP SHADE

Application filed June 16, 1930. Serial No. 36,071. Term of patent 3½ years.

To all whom it may concern:

Be it known that I, MARJORIE TONES KNIGHT, a citizen of the United States, residing in Des Moines, in the county of Polk and State of Iowa, have invented a new, original, and ornamental Design for a Lamp Shade, of which the following is a specification, reference being had to the accompanying drawings, forming a part thereof.

Fig. 1, is a side view of the lamp shade, and Fig. 2, is a top plan view of the lamp shade showing my new design.

I claim:

The ornamental design for a lamp shade as shown.

MARJORIE TONES KNIGHT.
